UNITED STATES PATENT OFFICE.

CHARLES H. KEENEY, OF AVON, CONNECTICUT.

EXHAUST FAN.

Application filed August 10, 1926. Serial No. 128,442.

This invention relates to the construction of those exhaust fans which are designed to collect from machines and discharge into bins or to the atmosphere, grinding dust, 5 granite dust, tumbling barrel dust, cement, shavings, chips and the other materials, polished or cut from stock during the process of manufacture, also for handling grain, smoke, odors and acid fumes, in fact any material 10 which it is desired to transfer by air currents. The machine built according to this invention is particularly serviceable for transferring material which ordinarily subjects the fan to considerable destructive 15 wear, as its suction inlet is adjacent to the discharge outlet, rather than central with the axis of the fan, whereby the material drawn in is immediately discharged without passing through the fan wheel or around 20 the casing, and thereby eliminating destructive wear on the casing and fan blades and preventing any clogging and unbalancing of the wheel.

The object of the invention is to so arrange 25 the suction inlet of an exhaust fan of this type, that in a simple and cheap way the efficiency of operation of the fan is increased and the wear of the parts is greatly reduced.

In the embodiment of the invention illustrated 30 this object is attained by locating the suction inlet at the side of a practically circular casing below the axis of the fan wheel and adjacent to the discharge outlet which is in the periphery of the casing, the inlet 35 opening being just in front of the discharge opening with relation to the direction of rotation of the fan wheel. A deflector is arranged in the interior of the casing in continuation with the inlet and extending 40 adjacent to the path of the fan in such position and of such shape that the air currents produced by the rotation of the fan cannot blow back into the inlet but will be caused to flow around the deflector and draw 45 material in through the inlet and at once discharge it through the outlet. A shield is located across the lower part of the casing between the deflector and the fan to eliminate the possibility of any material striking 50 or entering the fan as it passes from the inlet to the discharge.

In the accompanying drawings Fig. 1 shows a vertical section of a machine that embodies the invention, with the fan wheel, shield, and a portion of the casing side plate 55 which carries the inlet fitting, in side ele-

vation. Fig. 2 is a view looking down with the casing, intake, deflector and fan wheel in section. Fig. 3 is a perspective view on larger scale of the casing side plate which 60 carries the inlet fitting and the deflector.

The casing of the machine has a circular peripheral wall 1, of sheet steel, with a tangential discharge outlet 2. Attached to the casing on one side is a plate 3 and on the 65 other side is a plate 4, which plates are sheet steel and close the sides of the fan chamber. In the plate 4 below the center of the casing and adjacent to the outlet is the inlet opening 5. Attached to the outside of this plate 70 around the inlet is the inlet fitting 6. The inlet opening is somewhat wider than it is high, extending toward the discharge opening. The inlet fitting is circular in cross section at its outer end, that is, the end to 75 which the usual piping from the source of material to be collected is connected, and increases in width toward the outlet until it joins the side plate, at which locality the fitting is substantially oval in cross section 80 and conforms to the inlet opening.

Attached to the inside of the side plate 4 and conforming to and surrounding a portion of the inlet opening is the deflector 7. This shield extends inward obliquely toward 85 the path of the fan wheel from the side plate a considerable distance on the side of the inlet opening which is furthest from the outlet opening, and while conforming in cross section to the inlet opening, its end is 90 cut off obliquely to the axis so that on the outlet side it is reduced to practically nothing.

The shield 8 is a plate of sheet metal arranged across the lower part of the casing 95 between the deflector and the fan path. The outer edge of the shield is cut off at an angle.

The fan wheel illustrated has a conical body 9 fastened to a hub 10. Substantially 100 radial fan blades 11 are attached to the outer face of this body and hub. The hub is fastened to the end of the shaft 12. This shaft extends through the center of the side plate 3 and is supported by suitable bearings 13 between which it carries a driving 105 pulley 14 that is designed to be belted so as to turn the fan in the direction directed by the arrow on Fig. 1.

When the fan is rotated air is drawn in 110 through the inlet and discharged through the outlet carrying with it the material to be conveyed. The deflector prevents the air

2

currents produced by the fan from blowing back through the inlet and directs the conveyed material to the outlet. As the air passes around the tapering deflector and past its end a powerful suction effect is produced at the inlet. As the inlet fitting tapers toward the outlet and the air currents are directed by the tapering deflector toward the outlet the flow is such that all material drawn in is immediately delivered directly to the outlet with considerable velocity and without passing through the wheel or being carried around the casing. Furthermore the shield prevents any of the solid material from being carried into the fan. This not only increases the efficiency of the machine for the material is immediately discharged from it, but it also eliminates the abrading wear on the casing and fan blades which results in those machines which are so designed as to carry the solid material around with the fan from the inlet to the discharge.

The invention claimed is:—

1. An exhaust fan comprising a substantially circular casing, a fan wheel rotatable within the casing, said casing having a tangential discharge opening and an inlet opening through one side eccentric to the fan wheel axis and adjacent to the discharge opening, and means fixed within the casing for deflecting material from the inlet to the discharge, whereby material drawn into the casing by the rotation of the fan wheel is immediately discharged and not carried around by the fan wheel.
2. An exhaust fan comprising a substantially circular casing, a fan wheel rotatable within the casing, said casing having a tangential discharge opening and an inlet opening through one side eccentric to the fan wheel axis, and a deflector within the casing, said deflector extending inward from and conforming to a portion of the inlet opening and directing material therefrom toward the discharge opening.
3. An exhaust fan comprising a substantially cylindrical casing, a fan wheel rotatable within the casing, said casing having a tangential discharge opening and an inlet opening through one side eccentric to the fan axis and adjacent to the discharge opening, and a deflector within the casing, said deflector conforming in cross section to a portion of the inlet opening and extending

inward further on the side distant from the discharge opening than on the side nearest the discharge opening.

4. An exhaust fan comprising a substantially circular casing, a fan wheel rotatable within the casing, said casing having a tangential discharge opening and an inlet opening through one side eccentric to the fan wheel axis and adjacent to the discharge opening, an intake fitting attached to the side of the casing and conforming to the inlet opening, and a deflector extending inward from and conforming to a portion of the inlet opening, said deflector having its inner end cut off obliquely to the axis of the deflector and opening toward the discharge opening.

5. An exhaust fan comprising a substantially circular casing, a fan wheel rotatable within the casing, said casing having a tangential discharge opening and an inlet opening through one side below the axis of the fan wheel and adjacent to the discharge opening, and a shield extending across the lower part of the casing between the inlet opening and the fan path to prevent the passage of material from the inlet opening to the fan path.

6. An exhaust fan comprising a substantially circular casing, a fan wheel rotatable within the casing, said casing having a tangential discharge opening and an inlet opening through one side eccentric to the fan wheel axis and adjacent to the discharge opening, and a deflector within the casing and conforming to a portion of the inlet opening, said deflector extending inward obliquely from the inlet opening toward the fan path.

7. An exhaust fan comprising a substantially circular casing, a fan wheel rotatable within the casing, said casing having a tangential discharge opening and an inlet opening through one side below the axis of the fan wheel and adjacent to the discharge opening, a deflector within the casing and conforming to a portion of the inlet opening, said deflector extending obliquely inward from the inlet opening toward the fan path, and a shield arranged across the lower part of the casing opposite the inlet opening and between the deflector and the fan path.

CHARLES H. KEENEY.
